GOLF BALL CARRIER

John T. Kolarik, Sea Cliff, N.Y., assignor of one-half to Valentine F. Gabriel, Plainedge, N.Y.

Filed Oct. 5, 1960, Ser. No. 62,385

Term of patent 14 years

(Cl. D34—5)

FIG. 4

FIG. 1

FIG. 2

FIG. 1 is a front elevational view of a golf ball carrier showing my new design,

FIG. 2 is a side view of FIG. 1, the opposite side thereof being substantially the same,

FIG. 3 is a rear view of FIG. 1,

FIG. 4 is a top view of FIG. 2, and

FIG. 5 is a bottom view of FIG. 2.

I claim:

The ornamental design for a golf ball carrier, substantially as shown.
